(57) **CLAIM**

I claim the ornamental design for a canopy, as shown and described.

DESCRIPTION

FIG. 1 is a top perspective view of a first variant of the design; FIG. 2 is a front end elevation view of the first variant (with the rear end elevation view being identical);

FIG. 3 is a left side elevation view of the first variant (with the right side elevation view being identical);

FIG. 4 is a top plan view of the first variant;

FIG. 5 is a bottom plan view of the first variant;

FIG. 6 is a perspective view of the first variant installed on a work surface as environment;

FIG. 7 is a top perspective view of a second variant of the design;

FIG. 8 is a front end elevation view of the second variant (with the rear end elevation view being identical);

FIG. 9 is left side elevation view of the second variant (with the right side elevation view being identical),

FIG. 10 is a top plan view of the second variant;

FIG. 11 is a bottom plan view of the second variant; and,

FIG. 12 is a perspective view of the second variant installed on a work surface as environment.

The claimed design in the second variant is broken in the center to show indeterminate length.
